J. B. GLEASON.
CAR COUPLING.

No. 259,129.

Patented June 6, 1882.

UNITED STATES PATENT OFFICE.

JOHN B. GLEASON, OF DAYTON, ASSIGNOR TO HIMSELF AND CATHARINE M. GLEESON, OF CLEVELAND, OHIO.

CAR-COUPING.

SPECIFICATION forming part of Letters Patent No. 259,129, dated June 6, 1882.

Application filed March 27, 1882. (Model.)

To all whom it may concern:

Be it known that I, JOHN B. GLEASON, of Dayton, in the county of Montgomery and State of Ohio, have invented a new and Improved Car-Coupling, of which the following is a full, clear, and exact description.

My invention relates to the hook-headed kind of car-couplings; and it consists of certain improvements in the arrangement of the hook and means for operating it, all as herein-after described.

Reference is to be had to the accompanying drawings, forming part of this specification, in which similar letters of reference indicate corresponding parts in all the figures.

Figure 1 is a plan view of the said improved car-coupling, with the platform of the car indicated in dotted lines. Fig. 2 is a side elevation, and Fig. 3 is a horizontal section.

20 A represents the draw-bar, of the kind commonly used, to which I apply a hook-headed catch, B, formed of the two parts U and V, of cast-iron, secured between the two parts W W, of wrought-iron, which hook is pivoted on a pin, C, between the two chocks a of the draw-bar, the said catch being considerably widened in the rear end, and said end having a concavity, D, with rounded projections E F at the corners.

30 Behind the said concave rear end is a sliding block, G, with its front end fitted to the concavity of the hook, and fitted to slide forward and backward between the chocks of the draw-bar, being guided and maintained in position by the projections H of its sides in the slots I of the draw-bar. Behind this sliding block is a strong spring, J, supported against the block K, permanently fixed behind it in the draw-bar, and pressing the sliding block

40 against the concave end of the hook B, or the corner E thereof, when the hook is open. The spring is secured in position by sockets in the blocks, into which the ends are entered.

There is a concavity, L, into which the corner E of the hook is engaged to hold the hook open, as in the position shown in Fig. 3.

45 The hook has a staple or eyebolt, M, in the back, near the head, in which an elbow-lever, N, engages to open and close the hook, the said lever being pivoted at O under the plat-

form, with its handle P projecting out to the side of the car, where it can be conveniently reached for coupling and uncoupling.

The corner F of the rear end of the hook is notched or forked to receive the end of a connecting-rod, Q, pivoted to it, and extending back and under the platform to the lever R, having a fulcrum at S to work the hook from the other side of the car. The lever R can be extended across under the car, as shown in dotted lines, Fig. 3, to couple and uncouple the car from either side by this device, thereby, if desired, dispensing with the elbow-lever N.

T represents a pin in the head of the draw-bar to prevent the hook from swinging open too far.

It will be seen that by removing the coupling-hook of the ordinary Miller coupler and punching the holes for the pin C the hooks of this improved arrangement can be applied to the draw-bar of that construction; also, that in case the hooks may become damaged they can be taken out and an ordinary coupling-link used instead.

This arrangement has the advantage of being worked from either side of the car, and also from the ground, and enables the draw-bar and hook-coupler to be applied to freight-cars. The ordinary or other applied contrivances may be used for working the hooks from the platform.

The function of the block G is to hold the hook securely in position when coupled, and prevent it from uncoupling when the draft slackens up; also to hold it in the open position. Its use enables this form of hook to be arranged on a pivot, in the place of the ordinary coupling-bolt, with the spring located in the draw-bar behind it.

Having thus fully described my invention, what I claim as new, and desire to secure by Letters Patent, is—

1. The combination, with the draw-head A and the sliding block G, having convex forward end, of the coupling-hook B, having the concave rear end, D, substantially as and for the purpose set forth.

2. The coupling-hook B, pivoted between the chocks of the draw-bar at C, and having concave rear end, D, and projection E, in combina-

- tion with the spring-pressed sliding convex-ended block G, having cavity L, and being also arranged on the draw-bar, substantially as specified.
- 5 3. The combination, with the draw-bar A and the spring-held coupling-hook B, provided with the projection F at its rear end, of the lever R and the connecting-rod Q, substantially as and for the purpose set forth.
- 10 4. The combination of hook-coupler B, pivoted on the draw-bar, as described, and having projections E and F, sliding block G, spring J, and levers O and Q, substantially as specified.
5. The pressure-block G, having convex front 15 end, and being arranged between the chocks of the draw-bar, with projections H in guide-slots I of the said bar, in combination with hook B, substantially as specified.
6. The combination of stop-pin T with the 20 hook B, pressure-block G, draw-bar A, and the lever N, substantially as specified.

JOHN B. GLEASON.
